UNITED STATES PATENT OFFICE

170,758

TETHERED BALL GAME APPARATUS

Alfred Katherton, also known as Alfred C. Kather,
San Francisco, Calif.

Application September 15, 1952, Serial No. 21,453

Term of patent 7 years

(Cl. D34—5)

To all whom it may concern:

Be it hereby known, that I, Alfred Katherton, also known as Alfred C. Kather, a citizen of the United States, residing at San Francisco, in the county of San Francisco, and State of California, have invented a new, original, and ornamental Design for a Tethered Ball Game Apparatus, of which the following is a specification, reference being had to the accompanying drawing, forming part thereof.

Fig. 1 is a perspective view of a tethered ball game apparatus, showing my new design, and

Fig. 2 is a side elevational view thereof.

I claim:

The ornamental design for a tethered ball game apparatus, as shown.

ALFRED KATHERTON,
Also known as ALFRED C. KATHER.
